UNITED STATES PATENT OFFICE.

CHARLES BALCOM, OF LYNN, MASSACHUSETTS.

LACED BOOT OR SHOE.

SPECIFICATION forming part of Letters Patent No. 644,347, dated February 27, 1900.

Application filed December 27, 1898. Serial No. 700,353. (No model.)

To all whom it may concern:

Be it known that I, CHARLES BALCOM, of Lynn, in the county of Essex and State of Massachusetts, have invented certain new and useful Improvements in Laced Boots or Shoes, of which the following is a specification.

My invention relates to boots and shoes having lacing-engaging devices, such as hooks or studs, at opposite sides of the opening closed by the lacings; and it has for its object, first, to provide a boot or shoe of this character in which the opening shall be tightly closed by the lacing-cord, preventing the admission of water, snow, &c., at any point along the length of the opening, and, secondly, to provide in a stormproof boot or shoe of this class a durable and secure attachment of the lacing-engaging devices to the parts on which they are mounted.

The invention consists in the improvements which I will now proceed to describe and claim.

Of the accompanying drawings, forming a part of this specification, Figure 1 represents a side view of a stormproof boot embodying my invention. Fig. 2 represents an enlarged section on line 2 2 of Fig. 1. Fig. 3 represents a view of the lower end of the lacing-cord detached. Fig. 4 represents a perspective view showing another form of storm-proof boot embodying my invention. Fig. 5 represents a view similar to Fig. 2, showing a modification.

The same letters and numerals of reference indicate the same parts in all the figures.

Referring to Figs. 1 and 2, *a* represents the flap or fly which forms one side of the opening in the upper of a laced boot, said flap being constructed to overlap a portion of the quarter *b*.

c c represent a series of lacing-engaging devices, which are preferably lacing hooks or studs attached to the flap *a*, and *c' c'* represent a corresponding series of devices attached to the quarter *b*, the hooks or studs *c'* alternating with the hooks or studs *c*, so that by a single lacing-cord *d*, attached, as hereinafter described, to the boot, the hooks or studs *c'* can be engaged alternately with the hooks or studs *c* in the manner shown in Fig. 1.

The fly *a* and quarter *b* in a stormproof boot are composed of a part or layer 2, of textile fabric and rubber, and a lining 3, of textile

fabric. The part or layer 2 is made by combining or assembling unvulcanized rubber and fabric, and the lacing hooks or studs are secured to the layer 2 while in this condition—that is, before the vulcanizing process—each hook or stud having an attaching device *c*², (here shown as an eyelet,) which is inserted in the layer 2 and spread or upset to anchor it to the said layer. It will be understood, however, that the hooks or studs may have any other suitable attaching means. After the hooks or studs are thus secured to the unvulcanized layer 2 the lining 3 is applied to the inner surface of the layer 2, covering the attaching devices *c*² of the hooks or studs. The upper is subsequently vulcanized in the usual way, preferably after all the parts, including the rubber bottom, have been connected, all the rubber parts of the boot or shoe being vulcanized at one operation. It will be seen that by this construction the fastening devices *c*² are covered by the lining 3, and as said fastening devices are clenched or upset while the layer 2 is in a soft and plastic condition the clenched ends of the fastening devices sink into the layer 2, so that they do not form protuberances on its inner side, the added thickness of the upset portions of the fastening devices being thus compensated for. This is indicated in Fig. 2, in which there is also represented a reinforcing device *s*, hereinafter described. In said figure the reinforcing device and the clenched end of the fastening device are both sunk into the layer 2, so that they form no protuberance on the under side of said layer, and the lining 3 is perfectly smooth on its under surface of both the attaching and reinforcing devices. The parts of the upper and flap containing the lacing-engaging devices are therefore free from protuberances on their inner sides, so that the part in contact with the foot does not create discomfort to the wearer, while in the construction shown in Figs. 1 and 2 the inner surface of the flap is enabled to closely fit the outer surface of the quarter *b*, there being no protuberance 5 on the inner surface of the quarter. The described construction enables the lacing-cord *d* to press the flap closely against the quarter along the entire length of the flap, thus maintaining a tight joint between the two parts.

I secure the lower end of the lacing-cord d to the outer surface of the flap a by forming a loop d' on said lower end and causing said loop to encircle the fastening devices c^2 of the 5 lowest hook or stud c , so that when the said hook or stud is attached it will clamp and hold the loop d' firmly against the outer surface of the flap a , as shown in Fig. 2. The lacing therefore extends across and bears 10 downward upon the flap a at a point in close proximity to the point where said flap joins and is permanently connected to the quarter, so that there is no opportunity for the lower end of the flap to stand out from the quarter. 15 The lacing-cord is secured in the manner described before the vulcanizing operation, so that the loop is caused to indent the outer surface of the compressible flap a . The vulcanization of the rubber makes permanent 20 the indentations formed by the fastening and reinforcing devices and by the loop d' , so that the said parts are firmly held when the shoe is completed. Owing to the fact that the loop d' is firmly clamped against and some- 25 what embedded in the surface of the flap a , the said flap is pressed firmly down upon the portion of the shoe over which it laps when the cord has been engaged with the series of hooks or studs, whereby the shoe will be firmly 30 closed at the lower end of the opening, at which point moisture has been most liable to enter in shoes of this type as heretofore constructed.

In Fig. 4 I show the above-described improvements applied to a stormproof boot which is open in front and has two flaps d^3 d^4 , which overlap a bellows flap or tongue d^4 . One of the flaps d^3 is provided with a series 35 of lacing hooks or studs c and the other with a series of lacing hooks or studs c' , the manner of attaching the hooks or studs to the flaps d^3 and the manner of securing the lacing to the lowest lacing-engaging devices c being the same as that described in connection 40 with Figs. 1 and 2.

It will be seen that by the described method of attaching the lacing-engaging devices the inner surfaces of the flaps d^3 are left smooth and free from protuberances, so that they can 45 form tight joints on the flap d^4 , while the connection of the lower end of the lacing to the outer surface of the flap d^3 enables it to hold the tongue or flap down upon the tongue or flap d^4 .

s represents a reinforcing device which may be made of leather, metal, or any other suitable material which when engaged with the attaching members of the hooks or studs will prevent said members from being pulled out 50 of the layer 2. Said reinforcing device may be in the form of a strip engaged with a series of attaching devices c^2 or a series of smaller pieces or washers, each engaging one of said attaching devices. The thickness 55 added by the reinforcing devices is compensated for by the sinking of said devices, with the upset portions of the fastening devices,

into the compressible parts of rubber and fabric. The reinforcing device is here shown as placed in contact with the layer 2 in position 70 to receive the attaching devices c^2 ; but if desired it may be located at the inner side of the lining 3, in which case the attaching devices c^2 would pass through the said lining, as shown in Fig. 5, the lining being also 75 drawn inwardly by the upset portions of the fastening devices, so that its thickness is compensated for.

I claim—

1. A stormproof boot or shoe having two 80 compressible parts of fabric and rubber forming the sides of an opening, and cord-engaging members projecting from the outer surfaces of said parts and having fastening devices which extend through the compressible 85 parts and are turned or upset within said parts, the upset portions of the fastening devices indenting or compressing the surrounding compressible material before the same is vulcanized, to compensate for the thickness of 90 said upset portions, whereby the formation of projections on the inner surfaces of the compressible parts is prevented, and a lacing-cord engaged with said projections is enabled to maintain a tight joint between the 95 parts which it connects, the said compressible parts being strengthened by vulcanization after the compression of the portions surrounding the fastening devices.

2. A stormproof boot or shoe having two 100 compressible parts of fabric and rubber, forming the sides of an opening, cord-engaging members projecting from the outer surfaces of said parts and having fastening devices which extend through the compressible parts 105 and are turned or upset within said parts, and reinforcing devices which are interposed between the inner surfaces of the compressible parts and the upset portions of said fastening devices and surround the latter, the 110 said fastening and reinforcing devices being embedded in the compressible parts before vulcanization of the latter and causing the compression of the portions of the said parts which surround the fastening devices, to compensate for the thickness of the fastening and reinforcing devices, whereby the formation 115 of projections on the inner surfaces of the compressible parts is prevented, and a lacing-cord engaged with said projections is enabled to maintain a tight joint between the parts which it connects, the said compressible parts being strengthened by vulcanization after the compression of the portions surrounding the fastening devices.

3. A stormproof boot or shoe having two parts forming the sides of an opening, each part being composed of an outer compressible layer of fabric and rubber, and an inner layer or lining attached thereto, cord-engaging 130 members projecting outwardly from the outer surface of the outer layer of each part, and having fastening devices which extend through said compressible outer layers and

- are upset within the latter, and reinforcing devices which are interposed between the inner surfaces of the outer layers and the inner layers and surround the said fastening devices, the said fastening and reinforcing devices being embedded in the inner surface of the outer layers before vulcanization, which outer layers are compressed around the fastening devices to compensate for the thickness of the upset portions of the fastening devices and the reinforcing devices, whereby the formation of projections on the inner surfaces of the outer layers is prevented, so that the inner layers lie smoothly and without inward projections upon all the outer layers and reinforcing and fastening devices, the outer layers being strengthened by vulcanization after the compression of the portions surrounding the fastening devices.
- 20 4. A stormproof boot or shoe having two compressible parts of fabric and rubber, forming the sides of an opening, cord-engaging

members projecting from the outer surfaces of said parts and having fastening devices which extend through the compressible parts 25 and are upset within the latter and pressed into the inner surfaces of the compressible parts before vulcanization, and a lacing-cord having a loop which is interposed between the outer surface of one of the compressible parts 30 and the head of the lower cord - engaging member on said part and is pressed into the outer surface of said compressible part before vulcanization, the said compressible parts being subsequently vulcanized, so that the 35 indentations made therein by the fastening devices and the loop of the lacing-cord are made permanent.

In testimony whereof I have affixed my signature in presence of two witnesses.
